(57) **CLAIM**

The ornamental design for a container lid with a closure.

DESCRIPTION

FIG. 1 is a front elevational view of a container lid with a closure, showing my new design;

FIG. 2 is a left side elevational view thereof, the right side elevational view being identical thereto;

FIG. 3 is a top plan view thereof;

FIG. 4 is a bottom plan view thereof;

FIG. 5 is a rear elevational view thereof;

FIG. 6 is a front elevational view of the closure of FIG. 1, the rear elevational view being identical thereto;

FIG. 7 is a left side elevational view of the FIG. 6 closure, the right side elevational view being identical thereto;

FIG. 8 is a top plan view of the FIG. 6 closure;

FIG. 9 is a bottom plan view of the FIG. 6 closure; and,

FIG. 10 is a top perspective view of the FIG. 6 closure.
